UNITED STATES PATENT OFFICE.

JAMES W. PATTERSON, OF NEW YORK, N. Y.

COIN-OPERATED VENDING APPARATUS.

No. 796,010.

Specification of Letters Patent.

Patented Aug. 1, 1905.

Application filed April 26, 1902. Serial No. 104,752.

To all whom it may concern:

Be it known that I, JAMES W. PATTERSON, of the city, county, and State of New York, have invented an Improvement in Coin-Operated Vending Apparatus, of which the following is a specification.

My invention has reference to coin-controlled vending-machines; and it consists of certain improvements, all of which are fully set forth in the following specification and shown in the accompanying drawings, which form a part thereof.

The object of my invention is to provide a construction of apparatus which shall upon the deposition of the coin and its movement under mechanical hand manipulation deliver the contents of a receptacle, but unlike the usual vending-machines shall not be reset for a second delivery.

My invention has special availability as a vending-machine of compact form suitable for theater-chairs for vending a box of confections or opera-glasses, if desired; but in the latter case it is understood the glasses will be connected within the box of the machine by a chain to prevent them being stolen, since the coin in this case is for rental of the glasses during the performance.

My invention comprehends the following parts in combined form: A receptacle to contain the article for the purchase or use of which the coin is deposited, means for holding it securely in sealed condition, coin-controlled hand-operated means for unlocking or releasing the article and retaining the receptacle in unlocked condition, whereby it shall not reset or relock itself automatically.

My improvements also embody in such a mechanism a discharging-slot for the coin and a hand-controlled retaining device for normally retaining the coin against discharge, but permitting the same to be discharged by the insertion of a suitable key.

My invention also consists of many details of construction which will be better understood by reference to the drawings, in which—

Figure 1 is a front elevation of a vending-machine embodying my invention. Fig. 2 is a plan view of same. Fig. 3 is an inside elevation of the coin-controlled unlocking mechanism removed, taken on line 3 3 of Fig. 2. Fig. 4 is a cross-section of Fig. 1 on line 4 4. Fig. 5 is a sectional plan view of Fig. 1 on line 5 5. Fig. 6 is a sectional plan view of Fig. 1 on line 6 6. Fig. 7 is a sectional ele-

vation of Fig. 5 on line 7 7. Fig. 8 is an elevation similar to Fig. 3, showing a modified form of my invention. Fig. 9 is a cross-section of same on line 9 9, and Fig. 10 is a cross-section of same on line 10 10.

A is the box or case for containing the article. It is fitted with a vertically-movable floor C, pressed upward by the springs D D and having side guiding-arms c c. As shown, this floor C is adapted to support a box or package E, which when permitted is further elevated by a spring d, carried by the floor C, as shown in Fig. 4. The top of the case A is provided with a lid B, which is hinged at b and adapted to be locked down in position by locking-plate F and its bolts f. In the particular form shown the arms c press upward against the under side of the lid and force it open when released. At the same time that the lid is thrown back the article E is pushed up sufficiently high to enable it to be easily grasped and removed.

The coin-controlled lock-operating mechanism is contained in the flat-plate structure G, which is, with the several operating parts, formed by stamped sheet metal, thereby embodying cheapness, compactness, and simplicity of construction. The body portion of this structure is formed of a front plate and two rear plates stamped so as to receive the locking-plate F, the coin-retaining plate K, and the coin-moving disk I. The middle of the three flat plates is divided vertically to constitute the coin-passage H, which is enlarged at the middle to form a raceway for the coin and its operating-disk I. This disk I is notched so as to form one or more fingers or hook-shaped portions adapted to hook about the edge of the coin and propel it forward. This disk I is rotated by a handle J upon the outside and connecting with the disk by a spindle, as shown in Fig. 5.

The locking-plate F fits into a slotted portion g of one of the plates G and is provided at the top with the hooked portion or bolts f f for locking the lid B when closed. It is also provided with an outwardly-projecting lug F' at its bottom and extending into the coin-passage H when in normal locking position, as shown in dotted lines in Fig. 1. A spring O in the wall of the case A presses against the locking-plate to cause it to remain in any position assumed. When the coin S is moved down and around by the operating-disk I, it is caused to be forced against the lug F' of the locking-plate, and thereby become in-

strumental in shifting said plate and unlocking the lid. When the lid is unlocked and the handle J of the operating-disk I released, the coin drops down upon the retaining-plate K and remains there. This retaining-plate K is of the shape shown in Figs. 3 and 4 and 6, having a notched portion k forming a passage-way through which the coin may pass when such notch is brought into alignment with the coin-slot or raceway H in the plate structure G. This plate K fits into the recess L in the plate structures and is pressed in one direction by a spring l, so as to have its notch k out of alignment with the coin-slot H. It is also provided with a lateral end which enters a slot M in the plate structure G and is adapted to be operated by the long shank m of the key N being thrust into the slot and forcing back the plate K against the action of the spring l. In this manner the coin may be liberated and allowed to drop down through the coin-slot and removed. This structure obviates the necessity of a coin-receiving box or drawer and the complicated locking devices incident thereto. As shown, the end of the plate K is made wedge-shaped, so that if an attempt is made to liberate the coin by inserting a wire or narrow article it will wedge the plate instead of pushing it back.

It will be observed that the key-shank m is made notched to fit the shape of the plate and insure its being readily moved. I do not confine myself to any special shape of these parts, as they may be greatly varied where greater security is required.

To relock the box, it is only necessary to press down the lid B and then insert the shorter shank p of the key N into the slot P in the side of the plate structure G and push back the locking-plate, as shown in Fig. 3.

I have shown in Figs. 8, 9, and 10 a somewhat modified construction of the coin-propelling device and key-operated structure for discharging the coin, but the general features are the same as in the other figures. In this case the plate structure G' has the laterally-reciprocating locking plate or part F², provided with the locking-bolt portions f and the coin-actuated lug F³. The coin enters through the slot H and is supported by the retaining-plate K' in line with the lug F³ and also the push-bar or hand-controlled movable part I' for pushing the coin against the lug F³ to force back the plate F². This push-bar I is moved outward by a spring J² and is provided with a knob or hand operated part J'. The plate F² is pushed back, as before, by the end p of the key N being inserted through the slot P in the frame G'. The retaining-plate K' is guided in a slot L' and is normally held in retaining position by a spring l' of any suitable construction. This plate K' is also provided with a downwardly-extending lug K², which comes just above the line with the key-slot M. The key N has a long shank m, having a spring-

tongue n, the nose of which extends upward, as shown in Fig. 8. When the key is entered into the slot M, the nose n is forced inward and springs outward again when it passes the inner end of the slot. At this place it is in position to catch upon the lug K² of the retaining-plate and push it back to release the coin. When the key is withdrawn, the plate K' is moved back by the spring l'. The insertion of a rod or wire instead of the special key will not reach the lug K², and hence the lock cannot be easily picked. Of course it is evident that this principle of construction can be made more intricate where greater security against picking the lock is required, but for ordinary purposes it is not necessary, especially so when used in theaters or public places.

It will be observed that this machine is only for vending or delivering a single article or making a single delivery for one coin and is not intended to reset itself, as is customary with vending-machines as commonly found in use. Among the great merits of the apparatus herein set out are that it is inexpensive to construct, is simple, takes small space, and is not liable to get out of order.

While the box is shown as for vending a box of confections, I wish it to be understood that its special use is immaterial, as it may be adapted for any article, whether permanently removed or only removed for temporary use. Its shape may be varied and the mode of liberating the article may be varied as found most desirable. Therefore while I prefer the construction here set out the details may be varied without departing from the spirit of the invention.

Having now described my invention, what I claim as new, and desire to secure by Letters Patent, is—

1. In a vending-machine, the combination of a case to contain the article, a movable part to lock the article in the case, and a coin-controlled unlocking device consisting of a frame having a coin-slot open to the outside at both ends and formed throughout in a single plane, an unlocking device for the movable part formed of a sliding plate provided with locking parts and arranged to one side but parallel to the coin-slot and provided with a lateral lug directly operated by the movable part and coin to release the article, and a hand-operated part to move the coin through the slot and positively against the lateral lug of the unlocking device to cause it to slide for unlocking the movable part.

2. In a vending-machine, the combination of a case to contain the article, a movable part to lock the article in the case, and a coin-controlled unlocking device consisting of a frame having a coin-slot open to the outside at both ends and formed throughout in a single plane, an unlocking device for the movable part formed of a sliding plate provided with locking parts and arranged parallel to the coin-

slot and operated by the coin to release the article, a hand-operated part to move the coin through the slot and positively against the unlocking device to cause it to slide for unlocking the movable part, and a spring-actuated sliding retaining device adapted to slide in the plane of the coin-slot to normally assume a position to hold the coin after moving the unlocking device and adapted to be moved by hand against the action of the spring to release the coin and permit it to pass out of the coin-slot and then reset itself upon removal of the key.

3. In a vending-machine, the combination of a case to contain the article, a movable part to lock the article in the case, and a coin-controlled unlocking device arranged wholly at one side of the case and consisting of a frame having a coin-slot open to the outside at both ends and arranged throughout in one plane, an unlocking device for the movable part consisting of a flat sliding part or plate operated directly by the coin to release the article and adapted to remain where moved, a hand-operated part to move the coin in the slot and against the unlocking device for unlocking the movable part, a spring-actuated retaining device adapted to slide in the plane of the coin-slot to normally hold the coin after moving the unlocking device, and key-passages opening through the outside of the case and extending respectively to the unlocking device and the retaining device for the insertion of keys to move them.

4. In a vending-machine, the combination of a case to contain the article, a movable part to lock the article in the case, and a coin-controlled unlocking device arranged wholly at one side of the case and consisting of a frame having a coin-slot open to the outside at both ends and arranged throughout in one plane, an unlocking device for the movable part consisting of a flat sliding part or plate operated directly by the coin to release the article, a key-passage opening through the outside of the case and extending to the locking device for the insertion of a key to move it for locking the movable part, and a hand-operated part to move the coin in the slot and against the unlocking device for unlocking the movable part and releasing the article.

5. In a vending-machine, the combination of a case to contain the article, a movable lid to lock the article in the case, a spring-actuated support for the article within the case adapted to cause the lid to be raised and held in raised position independently of the article and also to cause the article to be moved out of the case when the lid is unlocked, and a coin-controlled unlocking device consisting of a frame having a coin-slot open to the outside at both ends and formed throughout in a single plane, an unlocking device for the movable part

formed of a sliding plate provided with locking parts and arranged parallel to the coin-slot and operated by the coin to release the article, and a rotating hand-operated part to move the coin in an arc of a circle in the slot and against the unlocking device or plate for unlocking the movable part.

6. In a vending-machine, the combination of a case to contain the article, a movable part to lock the article in the case, a spring-actuated support for the article within the case adapted to cause it to be moved out of the case when unlocked formed of spring-supported floor for pressing out the movable part or lid, and a spring carried thereby for elevating the article relatively to the floor, and a coin-controlled unlocking device consisting of a frame having a coin-slot open to the outside at both ends, an unlocking device for the movable part operated by the coin to release the article, and a hand-operated part to move the coin in the slot and against the unlocking device for unlocking the movable part.

7. In a vending-machine a case having a lid hinged at its rear, combined with a spring-actuated movable support within the case adapted to rise to elevate the article and to hold the lid from closing after it is raised and also to avoid pressure of the article upon the lid, a lock at the front of the case for locking the lid in a closed position and for holding the spring-actuated support in a depressed position, and a coin-controlled device arranged wholly at the front of the case for controlling the lock.

8. In a vending-machine, the combination of the case A having a pivoted lid B, with the movable floor C having side arms reaching to the underside of the lid for elevating it, springs to move the floor upward, a spring carried by the movable floor for elevating the article relatively to the floor, and a coin-controlled locking device for normally holding the lid closed.

9. In a vending-machine the combination of a case to contain the article, a movable lid for the case free to rise or fall, a movable part to lock the lid in closed position to secure the article in the case, a coin-controlled unlocking device having means adapted to act upon the coin for unlocking the movable part which locks the lid, and a spring-actuated support continuously pressing upward against the lid adapted to rise to lift and directly hold the lid of the case in an open position when released.

In testimony of which invention I have hereunto set my hand.

JAMES W. PATTERSON.
